LIGHTNING ARRESTER

Edward A. Everett, Long Island City, N. Y.

Application February 8, 1932, Serial No. 591,614

9 Claims. (Cl. 175—30)

This invention relates to lightning arresters, particularly of the resistor type and has for an object to provide an arrester having a base supporting a stem with a porcelain sleeve; to provide a flanged base on a porcelain sleeve for a grounded stem of an arrester and, to provide an assembly of parts which facilitates manufacture and replacement. Other objects of the invention will be more particularly understood from the following specification and the accompanying drawing, in which, Fig. 1, is an elevation of an arrester, partly sectioned, and mounted on an insulating base embodying my invention; Fig. 2, is a plan view on line 2—2, Fig. 1; Fig. 3, is a view on line 3—3 of Fig. 1; Fig. 4, is an elevation of the stem with the porcelain sleeve; Fig. 5, is a plan view looking from the top of the base, Fig. 6 is a modification of the construction shown in Fig. 1, and Fig. 7 is a sectional detail.

This invention comprises a lightning arrester mounted by terminal strips on the binding posts of a terminal block. The arrester comprises a base, preferably of moulded insulation such as bakelite which has projecting wings on each side connecting to the terminal strips. This base is provided with a hollow core and a central aperture in which the grounding stem of the arrester is mounted. This stem is splined on a spider member which is imbedded in the insulation of the base so that when the member is secured in position it is rigidly supported on the base with a non-turning support. The stem is provided with a porcelain sleeve having a flange base at the lower end which rests in the core of the insulating base and insulates the stem from the conducting strips. It has been found in practice that the use of a porcelain sleeve on the stem is highly desirable and under the effect of continued lightning discharges does not materially change its characteristics.

In order to guard against the possibility of the porcelain sleeve becoming fractured, it is loosely mounted on the terminal stem and rests on a yieldable gasket so that it is not influenced by temperature changes. The device is constructed to provide comparatively large spark gap surfaces between conducting parts and to facilitate the lightning discharge through a resistor block.

This invention is an improvement upon the construction shown in my co-pending application Serial No. 494,164, filed Nov. 7, 1930.

In the drawing, 11 is a terminal block on which the binding posts 12 and 13 are mounted. The binding post 12 clamps the terminal strip 15 and

the binding post 13 clamps the terminal strip 16. The insulated base 19 is provided with grooves as indicated at 20, Fig. 5, and in one of these grooves the terminal strip 15 is secured by the eyelet 17 and in the opposite groove the terminal strip 16 is secured by the eyelet 18. The sides of the base are substantially flushed with the top of the strips 15 and 16.

The central post 21, which is used for the ground connection through the terminal nuts 14 is secured to the base 19 by a splined connection as indicated at 24 with the spider 23, Fig. 3, which enters the corresponding depression 23a in the base and is fastened in position by the nut 22 through stem 21. This provides a vertical non-turning stem in the base 19 and enables the base to be moulded without the stem. The spider 23 is mounted in a depression on the raised ledge 25 of the base which is separated from the walls of the core as indicated at 26.

A gasket 27 of cork or other yieldable material is placed on the stem and between this gasket and the collar 30 the sleeve 29 is placed as shown. This sleeve is made from porcelain and has a flanged base as indicated at 28 which is located in the core of the base 19. The stem is assembled as shown in Fig. 4 before it is secured to the base 19.

The resistor block 41 which is shown in the drawing as cylindrical in shape is placed on the sleeve 29 and may be provided on the top with an insulated washer 42 of mica. This washer may be placed on the bottom or a washer may be placed on top and bottom if desired. The resistor block 41 is clamped upon the terminal strips 15 and 16 by the spring washer 43 which is clamped by the sleeve 44 on the stem 31 and which also engages the gasket 45 resting upon the cover 46, and securing the cylindrical transparent housing 47 on the gasket 48 for enclosing the resistor block.

The use of the insulated washer 42 is optional and is usually provided only when the lightning is to be shunted between the terminal strips 15 and 16, through the resistance block 41. Its use secures a high insulation test to ground for line wires connected to the arrester. When the discharge from the terminal strips 15 and 16 is made through the resistance block 41 to the ground connection at 14, the washer 42 may be omitted.

One object of the construction is to encourage the discharge of lightning over the outer surface of the block 41 and with this end in view the spring washer 43 engages the block 41 near its outer edge and the terminal strips 15 and 16 do not extend all the way in to the porcelain sleeve.

The flanges 28 on the base of the porcelain sleeve increase the discharging area over this part which effectively prevents lightning discharging through the core of the base 19 to the lower end of stem 21. 5 The discharge of lightning in this direction is further prevented by the annular depression 26 surrounding the ledge 25. Attention is called to the fact that as indicated in Figs. 2, 5 and 7 the base 19 is notched in the walls of the core at 32a. 10 immediately below the discharging points 32 of the terminal strips 15 and 16. It has been found in practice that by thus increasing the surface of insulation over which lightning has to discharge that it can be effectively prevented from taking 15 an undesirable path.

For instance, in Fig. 7, the lightning indicated by α follows the surface and the V groove but arcs across before reaching the apex of the groove. This prevents this part of the surface becoming 20 carbonized and tends to maintain the discharging conditions constant. If the groove were rectangular as indicated at 61 this condition would not be secured.

In Fig. 6 the terminal strip 15 is provided with 25 a wing 51 pivotally connected thereto at 52 and the terminal strip 16 has a corresponding wing 53 pivotally connected at 54. The wings or arms 51 and 53 enable the arrester to be connected to terminals spaced different distances apart without disturbing the relation of the terminal strips 15 and 16 to the discharge block 41.

Exhaustive tests made with this arrester show that it is capable of discharging lightning on low tension lines practically indefinitely without losing its effectiveness in discharging lightning and without lowering the normal resistance of the 35 circuits which it is used to protect.

Having thus described my invention, I claim:

1. A lightning arrester comprising a conductor, a base of insulation having a core formed 40 therein mounted on said conductor, a stem secured to said base, a porcelain sleeve mounted on said stem having a flange located in the core of said base engaged by said conductor, a resistor surrounding said sleeve and having one 45 face engaging said conductor and means connecting the opposite face of said resistor with said stem.

2. A lightning arrester comprising a conductor, a base of insulation mounted on said conductor, a stem secured to said base, a porcelain sleeve loosely mounted on said stem, a yieldable gasket on said stem engaging said sleeve, a resistor surrounding said sleeve and resting on 50 said conductor, and spring means connecting said resistor with said stem.

3. A lightning arrester, comprising a conductor, a base with a hollow core mounted on said conductor, a raised ledge on bottom of said core,

a spider, a groove on said ledge matching said spider, a stem splined to said spider, means for securing said stem to said base, a sleeve of insulation on said stem, a resistor on said sleeve resting on said conductor and means connecting said resistor with said stem. 5

4. A lightning arrester comprising a pair of fixed terminal strips, a base of insulation, grooved to receive said strips, a stem on said base, a resistor centered on said stem forming a connection between said stem and said strips and pivoted arms connected to said strips. 10

5. A lightning arrester comprising a pair of conducting strips having an aperture therebetween, a base of insulation, said strips mounted 15 in a groove in said base to leave an aperture therebetween, a stem secured to said base projecting through said aperture, a sleeve on said stem, discharging means connected between said stem and said strip, and an arm pivotally connected to each of said strips. 20

6. A lightning arrester comprising a conductor, a base of insulation mounted on said conductor having a core formed therein, a stem secured to said base, a porcelain sleeve loosely 25 mounted on said stem having its lower end located in the core of the base and a resistor mounted on said sleeve in contact with said conductor and means connecting said resistor in discharge relation with said stem. 30

7. A lightning arrester comprising a conductor strip with an aperture therein, a base of insulation mounted on said strip, a stem secured to said base, a porcelain sleeve on said stem passing through the aperture in said strip, a gasket 35 engaging one end of said sleeve and a collar on said stem engaging the other end of said sleeve, and a resistor mounted on said sleeve forming a path for lightning between said stem and said conductor strip. 40

8. A lightning arrester comprising a conductor, a base of insulation mounted on said conductor having a core with notches formed therein, said conductor extending in discharge points over the notches in said core, a stem in said core, 45 a porcelain sleeve on said stem, and a resistor block mounted on said sleeve forming a path for lightning between said stem and said conductor.

9. A lightning arrester comprising a conducting strip having a semi-circular end, a base of 50 insulation mounted on said strip, a stem secured to said base, a porcelain sleeve on said stem concentric with said semi-circular end, a gasket engaging one end of said sleeve and a collar on said stem engaging the other end of said sleeve 55 and a resistor mounted on said sleeve and forming a path for lightning between said stem and said conductor strip.

EDWARD A. EVERETT.
